UNITED STATES PATENT OFFICE

109,227

DESIGN FOR A CLOCK

Frederick Lux, Waterbury, Conn., assignor to The Lux Clock Manufacturing Co., Inc., Waterbury, Conn., a corporation of Connecticut

Application February 28, 1938, Serial No. 75,456

Term of patent 7 years

To all whom it may concern:

Be it known that Frederick Lux, a citizen of the United States and resident of Waterbury, in the county of New Haven and State of Connecticut, has invented a new, original, and ornamental Design for a Clock, of which the following is a specification, reference being had to the accompanying drawing, forming part thereof, and in which

Fig. 1 is a top view of a clock, showing my design, and

Fig. 2 is a side elevation thereof.

The dominant features of the design reside in the dial ornamentation, representing the sun with rays emanating therefrom, in the hand extending vertically above the dial, and in the pedestal upon which the dial rests.

I claim:

The ornamental design for a clock as shown and described.

FREDERICK LUX.
